UNITED STATES PATENT OFFICE.

JOHN J. MAHER, OF PROVIDENCE, RHODE ISLAND.

BOX-CLEAT-NAILING MACHINE.

Application filed May 27, 1925. Serial No. 33,102.

This invention relates to an improvement in box cleat nailing machine of the type more particularly employed in nailing wooden cleats about the edges of a sheet of veneer to form the walls of a box, and the object of this invention is to provide in such a machine a side gage to cooperate with the back gage to assist in positioning the short cleats and also to determine the extent of overhang of the veneer for the reception of the long cleats prior to the nailing operations.

With these and other objects in view, the invention consists of certain novel features of construction, as will be more fully described, and particularly pointed out in the appended claims.

In the accompanying drawings:

Figure 1 is a perspective view of my improved adjustable gage.

Figure 2 is a sectional side elevation illustrating my improved gage as secured to the table of a box cleat nailing machine.

Figure 3 is a perspective view illustrating the under side of the bracket to which my improved gage is adjustably attached.

Figure 4 is a perspective view illustrating a portion of the table of a box cleat nailing machine with the back gage mounted thereon and my improved edge gage secured to the side of the table to cooperate with the back gage in positioning the cleats and veneer prior to the nailing operations.

Figure 5 is a section of Figure 4 illustrating the nailing machine table and the means by which it is raised and lowered relative to the riveting plate which serves to rivet the pointed ends of the nails into the cleat.

Figure 6 is a top view of the construction illustrated in Figure 7 showing the back gage and the edge gage as cooperating to assist in positioning the short cleat and the sheet of veneer, the latter being illustrated in dotted lines.

Figure 7 is an edge view of the nailing machine table as shown in Figure 6, showing my edge gage as secured to the side of the table and a cleat and a sheet of veneer as positioned thereon.

Figure 8 is a perspective view illustrating a strip of veneer with the short cleat blocks nailed across the ends thereof in the manner illustrated in Figures 6 and 7.

Figure 9 is a perspective view of a strip of veneer to which both the short cleats and

the longer cleats have been nailed about the edge thereof.

Figure 10 is an edge view of the nailing machine table showing the position taken by the veneer and cleats in positioning the long cleats after the first operation of nailing the short cleats to the veneer.

Figure 11 is the same as Figure 10 illustrating the back gage against which the long cleat is positioned with one end lying against the side gage and the veneer shown in dotted lines as positioned by the two gages to be nailed to the long cleats.

Figure 12 is a perspective view showing one type of box formed on the nailing machine with my improved type of gage in which the cleats are positioned about the edge of the sheet of veneer and on the outside of the box.

It is found in the practical construction and operation of cleat nailing machines of this character, of advantage to provide a side gage on the table of the nailing machine to cooperate with the back gage thereon, whereby the cleats upon being positioned on the table are first pressed against the back gage and then forced endwise until their ends abut against the edge gage, the thickness of this edge gage being substantially that of the cleat; next the sheet of veneer is placed on the cleat with its rear edge against the back gage and is then carried sidewise until its side edge extends beyond the cleat to overhang the same and engage the upper side gage block, the overhanging portion being just the width of the long cleat which is to be subsequently nailed against this overhanging edge. As soon as the veneer is in position against both the

back and side gages, the foot operating pedal is pressed and the nails are fed to and driven through the veneer and the cleat, their points extending into the space below the cleat. The continued operation of the machine then lowers the table with its work also the hammers bringing the points of the nails into contact with the riveting blocks which turn these points over into the under face of the cleat, the table then returns to its original level ready for a repetition of operations.

The sheet of veneer with its cleat nailed to one end thereof is now reversed end for end and the operation is repeated to nail another short cleat to the opposite end thereof. After this is done a long cleat is positioned, the same as the short cleats, the sheet of

veneer with its short cleats is now turned half way around with its overhanging edge extending over the long cleat and the ends of its short cleat abutting the side edges 5 of the longer cleat and these short cleats are caused to abut against the edge gage thus positioning the veneer relatively to the short cleat to receive the nails therethrough. This operation is repeated to nail the long 10 cleat on the opposite edge of the veneer, which completes the nailing of these four cleats to the veneer to complete one wall of the box to be subsequently assembled; and it is found in practice by the use of my improved side gage which performs four functions, first to assist in positioning the end of the short cleat, then to determine the amount of overhang of the veneer, and third to position the long cleat and finally to position 15 the veneer with its short cleat ready to be nailed to the long cleat thereby greatly facilitating these operations of the machine permitting very rapid and most accurate work to be produced; and the following is a detailed description of the present embodiment 20 of my invention showing one construction of gage by which these advantageous results may be accomplished:—

With reference to the drawings 10 designates the table of a nailing machine which is provided with a back gage 11 on its face and is provided with openings 12 in this face to receive the riveting plate 13', this table 10 being adapted to support the cleat 35 13 and after the nails have been driven through the veneer 14 and this cleat 13 by hammers 15 the table is dropped by a movement of the slide 16 thereby presenting the pointed end of the nail to the riveting surface 13' which cooperates with the continued downward stroke of the hammers to turn the pointed ends of the nails over into the under face of the cleat.

It is found in practice of great advantage in operating a nailing machine of this character to provide, in addition to the back gage 11, a side gage 17 so that the cleat upon being deposited upon the table and pressed against the back gage 11 may be slid endways until its extremity contacts with this gage 17 whereby the cleat is accurately positioned to receive the veneer plate 14 to be nailed thereto. To accomplish this in a simple and effective way, 45 I have provided an L-shaped bracket 18 having one arm 19 slotted and extending down along the edge of the table 10, the same being bolted thereto at 20 through this slot whereby a vertical adjustment of 50 the side gage may be obtained to accommodate cleats of different thicknesses, the other arm 21 of this bracket is slotted as at 22 and provided on its under side with a pair of parallelly spaced side walls 23 55 between which a binding nut 24 is arranged

to slide longitudinally, but is prevented from rotating.

This side gage 17 comprises a lower gage block 25 having a longitudinal groove 26 in its lower face for the reception of the 60 arm 21 of the supporting bracket on which this block 25 may be adjusted. On the upper face of this block, I have formed a guide rib 27 on which is adjustably mounted an upper guide block 28. Through 65 this rib is formed an elongated slot 29 and this upper guide block may be adjustably secured in position on this guide rib of the guide block by means of a bolt 30 which extends down through both blocks and is 70 threaded into the nut 24 below, this nut being provided with an operating handle 31 above, by means of which both of these blocks may be secured simultaneously in 75 adjusted position by a single operation of 80 this handle.

It will be noted that the thickness of this lower gage block 25 including its guide rib 27 or that portion thereof extending above the face of the table is substantially that of the thickness of the cleats being operated upon, whereby when the cleat is in position with its end abutting against this lower gage block its upper surface comes substantially flush with the upper surface 85 of this block so that when a sheet of veneer is placed upon this cleat its upper edge may overlap the end of the cleat to engage the surface of the upper gage block which is set back from the front edge of the lower 90 gage surface a distance substantially that of the width of the long cleat to be next nailed into position thereto, and the positioning of this upper gage block may be readily and accurately determined to correspond to the width of the long cleat to 95 be employed, by the graduations on the edge thereof by means of which it may be set to permit the proper overhang of the veneer so as to accurately receive the next 100 cleat to be nailed thereon.

My improved gage is very simple and practical to construct and may be quickly adjusted whereby cleats of various widths and thicknesses may be very accurately positioned, whereby the machine may be operated with great rapidity and accuracy.

The foregoing description is directed solely towards the construction illustrated, but I desire it to be understood that I reserve the privilege of resorting to all the mechanical changes to which the device is susceptible, the invention being defined and limited only by the terms of the appended 115 claims.

I claim:

1. In a box cleat nailing machine, a cleat supporting table having a back gage and a cooperating side and end gage attached adjacent one edge of the table having two 120

gaging surfaces arranged in different horizontal and vertical planes for engagement with the cleat and veneer respectively to determine their relative positions before being nailed one to the other, and means for vertically adjusting one of said gages.

2. In a box cleat nailing machine, a cleat supporting table having a back gage, a cooperating side gage supported on said table, said side gage having a lower gage block for the cleat and an upper gage block 10 slidable on said lower block to determine the extent that the veneer shall overlie the end of the cleat before the nailing operation, and means whereby said lower gage block 15 may be adjusted vertically to accommodate cleats of different thicknesses.

3. In a box cleat nailing machine, a cleat supporting table having a back gage, a 20 cooperating side gage comprising an L-shaped bracket adjustably mounted on the edge of said table and having a slotted arm extending outwardly therefrom, a lower slotted gage block grooved to slide on the 25 upper surface of said arm and overlie the top surface of said table, a guide rib on said block, an upper gage block having a groove to slide on said rib and a bolt passing through said 30 upper block and the slots in said lower block and bracket arm to bind the parts together and permit the blocks to be adjusted relatively to each other and relatively to said table.

35 4. In a box cleat nailing machine, a cleat supporting table having a back gage, a supporting bracket in one edge of said table, two cooperating side gage members adjustably mounted on said bracket, a binding 40 bolt extending through said members and

bracket, a nut on the lower end of said bolt, and a retaining strip along the lower surface of said bracket for engagement with said nut to prevent the rotation of the same upon turning of said binding bolt. 45

5. In a box cleat nailing machine, a cleat supporting table having a back gage, a vertically adjustable supporting bracket on one edge of said table, two superimposed side 50 gage members adjustably mounted on said bracket, means for binding both of said gage members in adjusted position to said bracket for determining the position of cleats of different widths and thicknesses 55 and the veneer thereon immediately prior to the nailing operation.

6. In a box cleat nailing machine, a cleat supporting table having a back gage, a cooperating side gage comprising a lower gage block grooved on its under side, means 60 extending into said groove to guide said block in movement, a guide rib on said block, an upper gage block having a groove to slide on said rib, and a bolt passing through said blocks to bind them in adjusted position. 65

7. In a box cleat nailing machine, a cleat supporting table having a back gage, a cooperating side gage comprising a lower slotted gage block grooved on its under side, 70 means extending into said groove to guide said lower block in its movement, a guide rib on said block, an upper gage block having a groove to slide on said rib, and a bolt passing through said upper block and slot in said lower block to bind the parts together and permit the blocks to be adjusted 75 relatively to each other.

In testimony whereof I affix my signature.

JOHN J. MAHER.
